GLUE DISPENSER

Francis C. Rodman, Garden City, and James E. Engel, Tottenville, Staten Island, N. Y., assignors to American Seal-Kap Corporation of Delaware, Wilmington, Del., a corporation of Delaware

Application April 30, 1946, Serial No. 666,152

4 Claims. (Cl. 91—43)

1

This invention relates to a device for applying a spot of an adhesive material such as glue to a paper wrapper.

The invention as illustrated herein, is shown as used in connection with the wrapping of nested stacks of milk bottle caps in the manner disclosed in the Goodwin Patent No. 2,266,547. The caps are then applied to the mouth of milk bottles by capping machines such as are shown in the Daniels Patent No. 2,068,165 and the Goodwin et al. Patent No. 2,325,163. These patents each show a capping machine having a cylindrical magazine adapted to receive a stack of milk bottle caps from which they are automatically fed and applied to successive milk bottles as they leave a filling machine. In commercial practice the stacks of caps are wrapped by rolling the same in wrapping paper in such a way that the wrapper may be sealed by a spot of adhesive applied to the wrapper adjacent one of the corners thereof. Generally a definite number of caps are wrapped in each wrapper, and they are shipped and stored in wrapped stacks. In loading the capping machine a wrapped stack of caps is placed in the magazine with the corner of the wrapper beyond the sealing spot extending out through a longitudinal slot in the magazine. The wrapper is removed by grasping this corner, and pulling on the same to break the seal and to unroll the wrapper from the stack of caps, leaving the stack of caps in the magazine in condition for use. The caps are thus charged into the magazine without being touched by the operator; an important sanitary consideration in modern dairies.

Heretofore the adhesive was applied to the wrapping paper either by a small brush or by mechanism of the type such as shown in the Dorsch Patent No. 2,156,804. Applying the adhesive by a brush is a slow process and it is practically impossible to apply the same amount of adhesive to successive sheets of wrapping paper. Either too much or too little adhesive is generally applied. When too much is applied the seal is not readily broken after a stack has been inserted in the capping machine magazine, and when too little is applied, the seal frequently breaks during handling. Prior known adhesive applying mechanisms are rather complicated and are not too efficient in operation.

The principal object of the present invention is to provide an apparatus for applying spots of glue to sheets of wrapping paper which is simple and efficient in operation and which will always apply the same amount of glue to successive sheets of wrapping paper presented thereto.

2

Other and more specific objects of the invention will be apparent from the following specification and the accompanying drawings forming a part thereof wherein:

5 Fig. 1 is a plan view showing a wrapping table and my improved glue spotter associated therewith;

Fig. 2 is a front elevation thereof;

Fig. 3 is a central vertical section through our 10 improved glue spotter showing the various parts thereof in their normal inoperative position;

Fig. 4 is a view similar to Fig. 3 showing the various parts in the position they assume after the initial operative movement of the device; and

15 Fig. 5 is a view similar to Figs. 3 and 4 showing the device after it has been brought into contact with a sheet of wrapping paper to apply a spot of glue thereto.

Referring now to the drawing by reference 20 characters, the numeral 1 indicates generally our improved glue spotter which when used in connection with the wrapping of nested stacks of bottle caps is usually associated with a wrapping table 2 as shown in Figs. 1 and 2. The table 2 has 25 a groove or trough 3 extending from side to side thereof, and a pair of spaced transversely extending guide rails 4 and 5 adjustably secured to the upper surface thereof.

In wrapping stacks of bottle caps a rectangular 30 sheet of wrapping paper 6 is first placed diagonally upon the table 2 with one corner 7 thereof beneath the glue spotter 1, as shown in Fig. 1. A stack of caps, the length of the stack being equal to the distance between the rails 4 and 5, is then laid upon the wrapping paper over the 35 groove or trough 3 and is pressed down thereinto. The lower corner 8 of the wrapper is then folded up over the stack, partially enclosing it, after which the opposite corners 9 and 10 of the wrapper are folded in toward each other enclosing the 40 ends of the stack. The glue spotter 1 is then operated to place a spot of glue on the corner 7 of the wrapper and the stack with the wrapper thus folded thereabout is rolled upon the table 45 2 until the spot of glue contacts the underlying wrapper and effectively seals it about the stack. The manner in which the wrapper is folded and rolled about a stack of caps is clearly disclosed in the aforesaid Goodwin Patent No. 2,266,547.

Our improved glue spotter 1 includes a glue pot 11 having its upper end closed by a cover 12 which is removably secured thereto by screws 13 extending upwardly from the pot 11 through bayonet slots 14 in the cover. It is supported in 50 operative relation to the table 2 by a bracket 15

having a vertical bore 16 therethrough in which the glue pot 11 is slidably mounted. The bracket 15 is rigidly secured to either the table 2 or to any suitable support adjacent thereto.

A disc 17 having a transversely extending slot 18 formed therein is mounted within the upper end of the glue pot 11 upon an annular shoulder 19. Formed integrally with and projecting downwardly from the disc 17 is a sleeve 20 which acts as a guide for a valve stem 21 slidably mounted therein. A frustro-conical valve 22 which is pinned to the lower reduced end of the valve stem 21 is adapted to open and close a complementary shaped port 23 in a block 24 which is disposed in the lower end of the glue pot 11. The valve 22 and the block 24 are made of hardened metal to resist wear due to operation. The valve stem 21 has an annular flange 25 formed integrally therewith a short distance below the upper end 26 thereof, and immediately below the flange 25 the valve stem 21 has a slot 27 therethrough.

The upper end 26 of the valve stem and the flange 25 extend into an axial recess 28 in the lower end of a cam 29. The cam 29 has a cylindrical portion 30 which is slidably mounted in a centrally disposed aperture 31 through the cover 12. A knob 32 is pinned to the cam 29 as indicated at 33. A coiled spring 34 mounted in a bore 35 in the upper end of the valve stem 21 biases the valve stem 21 and valve 22 downwardly to close the port 23 and at the same time urges the cam 29 upwardly in the aperture 31.

A pair of opposed bell crank levers 36 each having a vertical arm 37 and a horizontal arm 38 are pivotally supported in the slot 18 by pins 39. The horizontal arms 38 of the bell crank lever extend into the slot 27, through the valve stem 21, and the vertical arms 37 of the bell crank lever are in contact with the frustro-conical cam surface 40 of the cam 29.

A coiled spring 41 disposed about the glue pot 11 between an annular flange 42, about the upper end thereof, and the upper surface of the bracket 15 normally urges the device upwardly in the bore 16 to the position shown in Fig. 3. A ring 43 adjustably secured about the glue pot 11 by a set screw 44 limits this upward movement of the device in the bore 16.

Operation

In operation, glue in liquid form is placed in the glue pot 11 beneath the disc 17. This is done by loosening the screws 13, turning the cover 12 until the screw heads are in alignment with the enlarged ends of the bayonet slot 14 and then lifting the cover 12 and cam 29 off by the knob 32. The disc 17 and the mechanism carried thereby are then removed and the glue inserted. These parts are then replaced. The spring 34 will normally hold the valve 22 down, closing the port 23 and preventing glue escaping. The wrapping paper is placed in proper position beneath the device and the knob 32 is depressed by the operator. This depresses the cam 29 which through the frustro-conical surface 40 spreads the vertical arm 37 of the bell crank levers 36 and rocks the ends of the horizontal arms thereof upwardly. The upward movement of the ends of the bell crank arms 38 lifts the valve stem 21 and valve 22, from the position shown in Fig. 3 to the position shown in Fig. 4, opening the port 23 and allowing glue to flow into the annular space between the valve 22 and the port 23 and about the lower flattened end of the valve. Further depression of the knob 32 will move the

device downwardly in the bore 16 against the upward pressure of the spring 41, from the position shown in Fig. 4 to the position shown in Fig. 5 with the lower end of the device in contact with the wrapping paper. A spot of glue, the size of the lower end of the port 23 will then be applied to the wrapper. The operator then releases the knob 32 allowing the springs 34 and 41 to return the various elements of the device to the position shown in Fig. 3, ready for the next operation.

The device has been illustrated and described herein in connection with the wrapping of nested stacks of bottle caps, but that is only for the purposes of illustration as the device can be used equally well in many other environments where it is desired to successively apply spots of adhesive to articles.

From the foregoing it will be apparent to those skilled in this art that we have provided a simple and efficient mechanism for carrying out the objects of our invention; and it is to be understood that we are not limited to the specific construction shown herein as various modifications may be made therein within the scope of the appended claims.

What is claimed is:

1. In a device of the character described the combination of a support, a glue pot reciprocally mounted in a bore in said support, an outlet port in the lower end of said pot, a cover removably secured to the upper end of said pot, a cam reciprocally supported by said cover, a disc mounted in said pot, a pair of opposed bell crank levers pivotally supported by said disc in operative relation to said cam and adapted to be rocked about their pivots by the reciprocation of said cam, a valve operative to open and close said port, and operative connections between said bell crank levers and said valve for lifting said valve in response to downward movement of said cam.

2. In a device of the character described the combination of a support, a glue pot reciprocally mounted in a bore in said support, an outlet port in the lower end of said pot, a cover removably secured to the upper end of said pot, a cam reciprocally supported by said cover, a disc mounted in said pot, a valve guide secured to said disc, a valve stem slidably mounted in said guide, a valve operative to open and close said port secured to the lower end of said valve stem, a pair of opposed bell crank levers pivotally supported by said disc in operative relation to said cam and adapted to be rocked about their pivots by the reciprocation of said cam, and operative connections between said bell crank levers and the upper end of said valve stem.

3. In a device of the character described the combination of a support, a glue pot adapted to be moved manually in one direction reciprocally mounted in a bore in said support, spring means about the upper end of said pot operative to move said pot in the opposite direction, an adjustable stop limiting the movement of said pot effected by said spring means, an outlet port in the lower end of said pot, a cover removably secured to the upper end of said pot, a cam reciprocally supported by said cover, a disc mounted in said pot, a valve guide secured to said disc, a valve stem slidably mounted in said guide, a valve operative to open and close said port secured to the lower end of said valve stem, a pair of opposed bell crank levers pivotally supported by said disc in operative relation to said cam and adapted to be

rocked about their pivots by the reciprocation of said cam, and operative connections between said bell crank levers and the upper end of said valve stem.

4. In a device of the character described the combination of a glue pot, an outlet port in the lower end of said pot, a valve plunger operative to open and close said port, a pair of opposed bell crank levers mounted in said pot and connected to operate said valve plunger, a cam mounted to 10 reciprocate vertically, and an actuating plunger for said cam extending above said pot for manual actuation, said cam having a surface shaped to rock said bell crank levers to lift said valve plunger when said cam actuating plunger is depressed. 15
